[57] **CLAIM**

The ornamental design of a bracket for supporting animal feeders, as shown and described.

DESCRIPTION

FIG. 1 is a perspective view of a bracket for supporting an animal feeder in a bent position showing our new design;

FIG. 2 is a top plan view thereof in the original position;

FIG. 3 is a left side elevation view thereof;

FIG. 4 is a right side elevation view thereof;

FIG. 5 is a bottom plan view thereof;

FIG. 6 is an end elevational view thereof; and,

FIG. 7 is an opposite end elevational view thereof.

FIG. 1

FIG. 2

FIG. 3

FIG. 4

FIG. 5

FIG. 6

FIG. 7
